UNITED STATES PATENT OFFICE

PAUL J. SIMMEN, OF EDEN, NEW YORK, ASSIGNOR TO SIMMEN AUTOMATIC RAILWAY SIGNAL COMPANY, OF EDEN, NEW YORK, A CORPORATION OF ARIZONA

AUTOMATIC TRAIN CONTROL

Substitute for abandoned application Serial No. 650,247, filed July 9, 1923. This application filed September 5, 1928. Serial No. 304,133.

This invention relates to railways and particularly to the control of cars or trains thereon.

An important object of this invention is an arrangement and construction of train control whereby trackway means are enabled to create a plurality of distinctive conditions for the car or train, which distinctive conditions may be used to appropriately govern the train in a plurality of different ways.

The present application is a substitute for application Serial No. 650,247, filed July 9, 1923, and abandoned.

In describing the principle of the invention reference is had to an illustrative physical embodiment illustrated by a single schematic view in the drawing forming a part of this specification, which drawing illustrates the invention as applied to a car.

In the drawing an ordinary railroad tie is shown at 1. Mounted on this tie in the usual and ordinary manner are rails 2.

A car is illustrated as being on the rails 2 by the showing of the ordinary axle 3 and the wheels 4. Suitably supported on the ties 1 are train control rails 5, 6 and 7, which are electrically insulated from the track rails and consist of short sections of metal approximately 60 feet long and spaced at suitable locations along the track. The train control rails are inclined at the ends so as to form a ramp in the usual manner such as is shown in my prior Patent No.

1,140,623, granted May 25, 1915. Suitably supported on the frame of the locomotive or car, but electrically insulated therefrom, are three contact shoes 8, 9 and 10, so positioned as to make contact with train control rails 5, 6 and 7 respectively. Contact shoe 8 is hinged at 11 and when the contact shoe slides along the ramp or train control rail, the shoe is tilted so as to break contacts 12, 13 and 14.

When the shoe leaves the other end of the train control rail, a spring 15 forces the contact shoe to the normal position thus again closing contacts 12, 13 and 14. Contact shoe 9 is hinged at 16 and when not in contact with a train control rail, it is held by a suitable stop, not shown, in a hori-

zontal position but when entering upon a train control rail, is tilted thus compressing a spring 17 and when this shoe leaves the other end of the train control rail, spring 17 forces the shoe back to the normal or horizontal position. Contact shoe 10 is hinged at 18 and when not in contact with a train control rail, it is held by a suitable stop, not shown, in a horizontal position but when entering upon a train control rail, is tilted, thus compressing a spring 19 and when this shoe leaves the other end of the train control rail, spring 19 forces the shoe back to the normal position.

The locomotive or car also carries a polarized relay 20 and a three position alternating current relay 21. The armatures of these relays control their several circuits depending upon the character of the energization or the deenergization of the relays, and the armatures in turn control the circuits through the several signals designated as No. 1, No. 2, No. 3, No. 4, No. 5, No. 6, No. 7, No. 8, and No. 9. While these devices are shown as lamps and designated signals, they may equally as well represent electromagnetic devices to which motion is given depending upon whether the circuit is energized or deenergized, and such electromagnetic devices may be used for other purposes than, or in addition to, the display of signals to the engineer, such, as is well known in the art, as the proper control of speed control devices or pneumatic air-valves or both, or the throwing of track switches.

Train control rails 5, 6 and 7 may be placed transversely in any position in relation to the track rails and their position will usually be determined by the clearance lines of the equipment operating over the railway, but longitudinally they are of the same length and opposite each other.

Along the track are located the direct current sources such as batteries 22 and 23 and an alternating current source such as 24. A switch 25 controls the energization or deenergization of train control rail 5. When it is in contact with spring contact 26, train control rail 5 is positively energized. When it is in contact with spring contact 27, train

- control rail 5 is negatively energized. When the switch is open, train control rail 5 is de-energized in so far as direct current is concerned. The alternating current is controlled by a double pole switch 28, which is hinged at 29 and 30, and when the switch is in the right hand position, as shown in the figure, the pole member 31 makes contact with terminal 32 and the pole member 33 makes contact with terminal 34. When double pole switch 28 is in the left hand position, opposite to that as shown in the figure, pole member 31 makes contact with terminal 35 and pole member 33 makes contact with terminal 36. The alternating current source 24 has four terminals representing the zero, 90° plus, 90° minus and 180° phase positions. Train control rail 7 is permanently connected to the 90° plus terminal of the alternating current source and train control rail 6 is permanently connected to the 90° minus terminal of the alternating current source. When double pole switch 28 is in the position shown in the figure, thus making contact with terminals 32 and 34, train control rail 5 is energized with alternating current of a phase leading in respect to the phase present in the train control rails 6 and 7, and when double pole switch 28 is in the position opposite to that as shown in the figure, thus making contact with terminals 35 and 36, train control rail 5 is energized with alternating current of a phase lagging in respect to the phase present in the train control rails 6 and 7. When switch 28 is open, train control rail 5 is deenergized in so far as alternating current is concerned. The various circuits for conditioning the rail 5 with the several currents will be described hereinafter.
- Depending upon the character of energization of train control rail 5, the armatures of relay 20 and rotor of relay 21 assume certain positions, thus closing the circuit through one of the nine signal lamps.
- The circuit through signal No. 1 is closed when train control rail 5 is energized with positive direct current and also energized with leading alternating current with respect to alternating current in train control rails 6 and 7.
- The circuit through signal No. 2 is closed when train control rail 5 is energized with negative direct current and also energized with leading alternating current with respect to alternating current in train control rails 6 and 7.
- The circuit through signal No. 3 is closed when train control rail 5 is energized with positive direct current and also energized with lagging alternating current with respect to alternating current in train control rails 6 and 7.
- The circuit through signal No. 4 is closed when train control rail 5 is energized with negative direct current and also energized

with lagging alternating current with respect to alternating current in train control rails 6 and 7.

The circuit through signal No. 5 is closed when train control rail 5 is energized with positive direct current and deenergized with respect to alternating current.

The circuit through signal No. 6 is closed when train control rail 5 is energized with negative direct current and deenergized with respect to alternating current.

The circuit through signal No. 7 is closed when train control rail 5 is deenergized with respect to direct current and energized with leading alternating current with respect to alternating current in train control rails 6 and 7.

The circuit through signal No. 8 is closed when train control rail 5 is deenergized with respect to direct current and energized with lagging alternating current with respect to alternating current in train control rails 6 and 7.

The circuit through signal No. 9 is closed when train control rail 5 is deenergized both with respect to direct current and alternating current.

Switches 25 and 28 may be manually operable switches suitably housed in a way station, interlocking tower or dispatcher's office or they may equally as well represent armatures of track relays by which the nine different electrical conditions of train control rail 5 may be established automatically in a manner similar to that shown in my prior Patent No. 1,315,346 granted September 9, 1919, or some of the nine conditions may be controlled automatically by a track circuit and others by manually operable switches.

Polarized relay 20 controls neutral armatures 37, 38, 39 and 40 and polarized armatures 41, 42, 43, 44 and 45. When this relay is positively energized, its neutral armatures make contact with front contacts 46, 47, 48 and 49 respectively and the polarized armatures will be in the right hand position as shown in the figure and make contact with contacts 50, 51, 52, 53 and 54. When relay 20 is negatively energized, its neutral armatures will also make contact with their respective front contacts but the polarized armatures will assume the left hand position opposite to that shown in the figure and make contact with contacts 55, 56, 57, 58 and 59. When relay 20 is deenergized, its neutral armatures will drop away from their front contacts and armatures 38, 39 and 40 will then make contact with their respective back contacts 60, 61 and 62. Polarized armatures 44 and 45 are members of a pole changing switch for the purpose of changing the direction of flow of current from battery 71.

The three position, motor type, alternating current relay 21 has two windings 63 and 64. Its rotor 65 controls a contact arm 66. The

5 rotor of relay 21 is so balanced that when this relay is deenergized, the rotor will assume the neutral position as shown in the figure, and in this position contact arm 66 will make contact with contact 67. Contact arm 66 is insulated from the rotor by insulation 68. When windings 63 and 64 of motor relay 21 are energized and winding 64 is energized with leading current with respect to winding 63, the rotor 10 65 will rotate counter-clockwise and contact arm 66 will make contact with contact 69, and when windings 63 and 64 are energized and the current in winding 64 is lagging with respect to winding 63, the rotor 15 65 will rotate clockwise and contact arm 66 will make contact with contact 70.

20 When contact shoe 8 is in contact with positively energized train control rail 5, polarized relay 20 is positively energized through the following circuit: From positive pole of battery 22, wire 72, spring contact 26, switch 25, wire 73, impedance 74, wire 75, train control rail 5, contact shoe 8, wires 76 and 77, impedance 78, wire 79, polarized relay 20, wires 80, 81, 82, and 83, axle 3, wheel 4, track rail 2, wires 84 and 85, to negative pole of battery 22. When contact shoe 8 is in contact with negatively energized train control rail 5, polarized relay 20 is 25 negatively energized through the following circuit: From positive pole of battery 23, wire 86, wire 84, track rail 2, wheel 4, axle 3, wires 83, 82, 81 and 80, polarized relay 20, wire 79, impedance 78, wires 77 and 76, contact shoe 8, track rail 5, wire 75, impedance 74, wire 73, switch 25, spring contact 27, and wire 87 to the negative pole of battery 23.

30 When contact shoes 9 and 10 are in contact with train control rails 6 and 7, winding 63 of alternating current relay 21 is energized through the following circuit: From 90° plus terminal of alternating current source 24, wires 88 and 89, train control rail 7, contact shoe 10, wire 90, winding 63, wire 91, contact shoe 9, train control rail 6, wire 92, and wire 93 to the 90° minus terminal of alternating current source 24. As heretofore stated this winding is always energized with the same character of alternating current 35 when contact shoes 8, 9 and 10 are passing train control rails 5, 6 and 7. When contact shoe 8 is passing train control rail 5, with switch 28 in the position illustrated, winding 64 of relay 21 is energized with leading alternating current with respect to winding 63 through the following circuit: From zero terminal of alternating current source 24, wire 94, hinge 30, pole member 33, terminal 34, wire 95, terminal 35, wire 96, condenser 97, wires 98, and 75, train control rail 5, contact shoe 8, wires 76 and 99, condenser 100, wire 101, winding 64, wires 102, 81, 82 and 83, axle 3, wheel 4, track rail 2, wires 103 and 104, terminal 36, wire 105, terminal 32, pole member 31, hinge 29, and wire 106, to the 180°

70 terminal of alternating current source 24. When contact shoe 8 is passing train control rail 5, with switch 28 in the position opposite to that indicated, winding 64 of relay 21 is energized with lagging alternating current in respect to winding 63 through the following circuit: From 180° terminal of alternating current source 24, wire 106, hinge 29, pole member 31, terminal 35, wire 96, condenser 97, wires 98 and 75, train control rail 5, contact shoe 8, wires 76 and 99, condenser 100, wire 101, winding 64, wires 102, 81, 82 and 83, axle 3, wheel 4, track rail 2, wires 103 and 104, terminal 36, pole member 33, hinge 30 and wire 94, to zero terminal of alternating 75 current source 24. It will thus be seen that depending upon the position of switch 25, relay 20 may be positively energized or negatively energized or deenergized and depending upon the positions of the switch 28, rotor 65 of relay 21 may be turned counter-clockwise or clockwise or placed in the neutral position.

80 Impedances 74 and 78 are placed in the circuit of relay 20 to prevent the flow of alternating current therethrough and condensers 97 and 100 are inserted in the circuit of relay 21 to prevent the flow of direct current therethrough.

85 I will now describe the circuits through 95 which the signals No. 1 to No. 9, inclusive, are energized. When contact shoes 8, 9 and 10 are in contact with train control rails 5, 6 and 7 and switch 25 is in contact with spring contact 26, and switch 28 is in contact with terminals 32 and 34, then polarized relay 20 is positively energized and winding 64 of 100 relay 21 is energized with leading current with respect to winding 63, thus placing contact arm 66 in contact with contact 69. Under these conditions a circuit is closed through signal No. 1 as follows: From positive pole 105 of battery 71, wires 107 and 108, contact 53, polarized armature 44, wire 109, flexible connection 110, contact arm 66, contact 69, wire 111, armature 38, of relay 20, front contact 47, wire 112, polarized armature 41, contact 50, wire 113, signal No. 1, wires 114, 82 and 115, polarized armature 45, contact 54, wire 116 to negative pole of battery 71. When the 110 contact shoe leaves the train control rail, a stick circuit is closed through the polarized relay which continues to energize this relay positively as follows: From positive pole of battery 71, wires 107 and 108, contact 53, polarized armature 44, wire 117, armature 37 of 115 relay 20, front contact 46, wire 118, contact 12, contact shoe 8, wires 76 and 77, impedance 78, wire 79, polarized relay 20, wires 80, 81 and 115, polarized armature 45, contact 54, 120 and wire 116 to negative pole of battery 71. This stick circuit will be hereinafter referred to as the positive direct current stick circuit.

125 Contact arm 66 attached to rotor 65 is also maintained in contact with contact 69,

through the following arrangement: A locking magnet 119 controls an armature 120 mounted on a pivot 121. To the extension of armature 120 is attached a friction shoe 122. When locking magnet 119 is energized, armature 120 will press friction shoe 122 against rotor 65 or some part connected thereto such as its shaft thus holding the rotor in the position it is in by friction. When the locking magnet is deenergized, a spring 123 pulls armature 120 away from magnet 119 thus releasing the friction through friction shoe 122 upon rotor 65. When contact shoe 8 is not in contact with train control rail 5, contacts 13 and 14 are closed and thus a circuit is established through locking magnet 119 as follows: From battery 124, wire 125, locking magnet 119, wire 126, contact 18, contact plate 127, contact 14, and wire 128, to opposite pole of battery 124. Contact plate 127 is attached to shoe 8 but insulated therefrom. It will thus be seen that when shoe 8 is in contact with train control rail 5, contacts 13 and 14 are broken thus deenergizing locking magnet 119 and rotor 65 is free to assume any of its three positions. As soon however as contact shoe 8 reaches the low end of the train control rail and also when it leaves the other end of train control rail 5, contacts 13 and 14 are again made and locking magnet 119 is again energized, thus holding rotor 65 in the position it was placed in when passing the train control rail. This circuit which controls locking magnet 119 will be referred to hereinafter as the alternating current relay holding circuit. With the positive direct current circuit and the alternating current relay holding circuit both in effect, signal No. 1 is continued until the next train control rail is reached.

When contact shoes 8, 9 and 10 are in contact with train control rails 5, 6 and 7 and switch 25 is in contact with spring contact 27, and switch 28 is in contact with terminals 32 and 34, then polarized relay 20 is negatively energized and winding 64 is energized with leading current with respect to winding 63, thus placing contact arm 66 in contact with contact 69. Under these conditions a circuit is closed through signal No. 2, as follows: From positive pole of battery 71, wires 107 and 129, contact 59, polarized armature 45, wires 115, 82, 114 and 130, signal No. 2, wire 131, contact 55, polarized armature 41, wire 112, contact 47, armature 38 of relay 20, wire 111, contact 69, contact arm 66, flexible connection 110, wire 109, polarized armature 44, contact 58 and wire 116 to negative pole of battery 21. When the contact shoe leaves the train control rail a stick circuit is established through relay 20 which maintains this relay negatively energized as follows: From positive pole of battery 71, wires 107 and 129, contact 59, polarized armature 45, wires 115, 81 and 80, relay 20, wire 79, impedance 78,

wires 77 and 76, contact shoe 8, contact 12, wire 118, front contact 46, armature 37 of relay 20, wire 117, polarized armature 44, contact 58, and wire 116 to the negative pole of battery 71. This stick circuit will be referred to hereinafter as the negative direct current stick circuit. With the negative direct current stick circuit and the alternating current relay holding circuit both in effect, signal No. 2 is continued until the next train control rail is reached.

When contact shoes 8, 9 and 10 are in contact with train control rails 5, 6 and 7 and switch 25 is in contact with spring contact 26 and switch 28 is in contact with terminals 35 and 36, then polarized relay 20 is positively energized and winding 64 of relay 21 is energized with lagging current with respect to winding 63 thus placing contact arm 66 in contact with contact 70. Under these conditions a circuit is closed through signal No. 3 as follows: From positive pole of battery 71, wires 107 and 108, contact 53, polarized armature 44, wire 109, flexible connection 110, contact arm 66, contact 70, wire 132, armature 39 of relay 20, front contact 48, wire 133, armature 42, contact 51, wire 134, signal No. 3, wires 135, 114, 82 and 115, armature 45, contact 54, and wire 116 to negative pole of battery 71. When the contact shoe leaves the train control rail, the positive direct current stick circuit and the alternating current relay holding circuit are again both in effect and signal No. 3 is continued until the next train control rail is reached.

When contact shoes 8, 9 and 10 are in contact with train control rails 5, 6 and 7 and switch 25 is in contact with spring contact 27, and switch 28 is in contact with terminals 35 and 36, then polarized relay 20 is negatively energized and winding 64 of relay 21 is energized with lagging current with respect to winding 63 thus placing contact arm 66 in contact with contact 70. Under these conditions a circuit is closed through signal No. 4 as follows: From positive pole of battery 71, wires 107 and 129, contact 59, polarized armature 45, wires 115, 82, 114 and 136, signal No. 4, wire 137, contact 56, polarized armature 42, wire 133, front contact 48, armature 39 of relay 20, wire 132, contact 70, contact arm 66, flexible connection 110, wire 109, polarized armature 44, contact 58, and wire 116 to negative pole of battery 71. When the contact shoe leaves the train control rail, the negative direct current stick circuit and the alternating current relay holding circuit are again both in effect and signal No. 4 is continued until the next train control rail is reached.

When contact shoes 8, 9 and 10 are in contact with train control rails 5, 6 and 7, and switch 25 is in contact with spring contact 26 and switch 28 is open, then polarized relay 20 is positively energized and winding 64 of relay 21 is de-energized thus placing

contact arm 66 in contact with contact 67. Under these conditions a circuit is closed through signal No. 5 as follows: From positive pole of battery 71, wires 107 and 108, contact 53, polarized armature 44, wire 109, flexible connection 110, contact arm 66, contact 67, wire 138, armature 40 of relay 20, front contact 49, wire 139, polarized armature 43, contact 52, wire 140, signal No. 5, wires 141, 114, 82 and 115, polarized armature 45, contact 54, and wire 116 to negative pole of battery 71. When the contact shoe leaves the train control rail, the positive direct current stick circuit and the alternating current relay holding circuit are again both in effect, and signal No. 5 is continued until the next train control rail is reached.

When contact shoes 8, 9 and 10 are in contact with train control rails 5, 6 and 7, and switch 25 is in contact with spring contact 27, and switch 28 is open, then polarized relay 20 is negatively energized and winding 64 of relay 21 is de-energized thus placing contact arm 66 in contact with contact 67. Under these conditions a circuit is closed through signal No. 6 as follows: From positive pole of battery 71, wires 107 and 129, contact 59, polarized armature 45, wires 115, 82, 114, and 142 of Signal No. 6, wire 143, contact 57, polarized armature 43, wire 139, front contact 49, armature 40, wire 138, contact 67, contact arm 66, flexible connection 110, wire 109, polarized armature 44, contact 58, and wire 116 to negative pole of battery 71. When the contact shoe leaves the train control rail, the negative direct current stick circuit and the alternating current relay holding circuit are again both in effect and signal No. 6 is continued until the next train control rail is reached.

When contact shoes 8, 9 and 10 are in contact with train control rails 5, 6 and 7 and switch 25 is open, and switch 28 is in contact with terminals 32 and 34, then polarized relay 20 is de-energized, and winding 64, of relay 21, is energized with leading current with respect to winding 63, thus placing contact arm 66 in contact with contact 69. Under these conditions a circuit is closed through signal No. 7 as follows: From positive pole of battery 71, wires 107 and 108, contact 53, polarized armature 44, wire 109, flexible connection 110, contact arm 66, contact 69, wire 111, armature 38, back contact 60, wire 144, signal No. 7, wires 145, 114, 82 and 115, polarized armature 45, contact 54, and wire 116 to negative pole of battery 71. When the contact shoe leaves the train control rail, contact 12 is again made, but the stick circuit through relay 20 is now open at front contact 46. Thus both the positive and negative direct current stick circuits are inoperative, and relay 20 continues to be de-energized, but the alternating current relay holding circuit is in effect, and signal No. 7

is continued until the next train control rail is reached.

When contact shoes 8, 9 and 10 are in contact with train control rails 5, 6 and 7, and switch 25 is open, and switch 28 is in contact with terminals 35 and 36, then polarized relay 20 is de-energized, and winding 64 of relay 21 is energized with lagging current with respect to winding 63, thus placing contact arm 66 in contact with contact 70. Under these conditions a circuit is closed through signal No. 8, as follows: From positive pole of battery 71, wires 107 and 108, contact 53, polarized armature 44, wire 109, flexible connection 110, contact arm 66, contact 70, wire 132, armature 39, back contact 61, wire 146, signal No. 8, wires 147, 114, 82 and 115, polarized armature 45, contact 54, wire 116, to negative pole of battery 71. When the contact shoe leaves the train control rail the direct current stick circuit through relay 20 is again in-operative but the alternating current relay holding circuit is in effect and signal No. 8 is continued until the next train control rail is reached.

When contact shoes 8, 9 and 10 are in contact with train control rails 5, 6 and 7, and switches 25 and 28 are both open, then polarized relay 20 is de-energized and winding 64 of relay 21 is also de-energized, thus placing contact arm 66 in contact with contact 67. Under these conditions a circuit is closed through signal No. 9 as follows: From positive pole of battery 71, wires 107 and 108, contact 53, polarized armature 44, wire 109, flexible connection 110, contact arm 66, contact 67, wire 138, armature 40, back contact 62, wire 148, signal No. 9, wires 149, 114, 82 and 115, polarized armature 45, contact 54, and wire 116 to the negative pole of battery 71. When the contact shoe leaves the train control rail, the direct current stick circuit through relay 20 is inoperative, but the alternating current relay holding circuit is in effect and signal No. 9 is continued until an energized train control rail is reached.

The utility of the invention consists in providing a multiplicity of conditioned devices or signal indications. These may be automatically controlled by track circuits in which case they would indicate the gradual approach of a train on which they are located toward another train or other danger or they may be used to convey useful information to the engineer. The tendency in modern methods of train operation is to eliminate as far as possible telegraphic or telephonic train orders to the train crew, as such methods are the cause of frequent errors and expensive delays to trains. The invention described herein provides for as many as nine conditions or signal indications, all based on the normally closed circuit principle, thus giving opportunity for many different distinct instructions to the engineer, each signal im-

parting a certain instruction or order as the railway management may designate.

It is obvious that the nine conditions or signal indications may not necessarily be given on a car or train, but may be expressed through fixed signals or other apparatus along the right of way. To arrange the circuits for the control of fixed signals, it is only necessary to eliminate the use of train control rails and contact shoes and permanently connect the wires which are shown on the drawing as connected to the respective train control rails and contact shoes.

Although I have particularly described one of the physical embodiments of my invention and illustrated the same, nevertheless, I desire to have it understood that the particular form illustrated is merely illustrative and does not exhaust the possible embodiments of the idea or means underlying the principle of my invention.

What I claim as new and desire to secure by Letters Patent of the United States is:

1. In an automatic train control, in combination, a source of direct current, a second source of direct current, a source of alternating current of a plurality of phases, three ramps, connections between one of the ramps and the sources of direct current and between all of the ramps and the source of alternating current, switching means interposed in these connections, a vehicle, train control means on the vehicle, the means on the vehicle connecting at times with the ramps and connected to the vehicle control means whereby a plurality of conditions are created in the vehicle control means.

2. In an automatic train control, in combination, a vehicle, an alternating current relay on the vehicle having an armature, a polarized relay on the vehicle having an armature, and means including sources of direct current and a source of alternating current whereby the relay armatures are variously positioned, and means for utilizing the various positions to establish more than six different electrical circuits.

3. In an automatic train control in combination, a source of direct current, a second source of direct current, a source of alternating current of a plurality of phases, three ramps, connections between one of the ramps and the sources of direct current and between all of the ramps and the source of alternating current, switching means interposed in these connections, a vehicle, train control means on the vehicle including two different relays, the means on the vehicle connecting at times with the ramps and connected to the vehicle control means whereby more than six conditions are created in the vehicle control means.

4. In an automatic train control, in combination, a vehicle, a rotary alternating current relay on the vehicle having an armature,

a polarized relay on the vehicle having an armature, and means including sources of direct current and a source of alternating current whereby the relay armatures are variously positioned, and means for utilizing the various positions in more than six different ways.

5. An automatic train control system comprising a vehicle, more than six signals on the vehicle, a plurality of control relays for said signals on the vehicle, said relays being capable of assuming three positions, means for supplying currents of different kinds to said vehicle and said relays for causing each of said relays to assume predetermined positions in accordance with the kind of current supplied thereto, a plurality of signal circuits, one for each signal, a source of current for said signals, and means including said relay positions for establishing any one of said signal circuits depending upon the position of said relays.

6. An automatic train control system comprising a vehicle, more than six signals on the vehicle, a circuit for each of said signals, a plurality of relays on the vehicle, each relay being responsive to a plurality of currents of different kinds and assuming a predetermined position when energized with any one of said currents, a source of current for said signals, and means along the trackway for characteristically energizing said relays to cause the armatures thereof to assume predetermined positions, said positions when established completing a circuit through a predetermined signal circuit and said source of current.

7. An automatic train control system comprising a vehicle, more than six signals on the vehicle, a circuit for each of said signals, a plurality of relays on the vehicle, each relay being responsive to a plurality of currents of different kinds and assuming a predetermined position when energized with any one of said currents, a source of current for said signals, means along the trackway for characteristically energizing said relays to cause the armatures thereof to assume predetermined positions, said positions when established completing a circuit through a predetermined signal circuit and said source of current, and means for maintaining said signal circuit until changed by the means along the trackway.
